UNITED STATES PATENT OFFICE.

AUGUST L. WEINERT, JR., AND FRED TUKA, OF NEWARK, NEW JERSEY.

VALVE-TRUING DEVICE.

Application filed November 12, 1921. Serial No. 514,453.

To all whom it may concern:

Be it known that we, AUGUST L. WEINERT, Jr., and FRED TUKA, citizens of the United States, and residents of Newark, Essex County, New Jersey, have invented certain new and useful Improvements in Valve-Truing Devices, of which the following is a description.

Our invention relates to valve truing devices and more particularly to an improved device of this character for effectively and correctly dressing and truing the faces of poppet valves such as are ordinarily employed in internal combustion engines, so that such faces will be perfectly concentric with the stems of the valves and will exactly conform to the seats with which the valves are designed to cooperate.

It is also an object of our invention to provide in a device of the character indicated an improved construction and arrangement for centering a valve to be trued and for maintaining the valve correctly centered in the device throughout the truing or dressing operation.

Our invention further resides in a novel arrangement for securing a valve in a device of this character, which preferably includes the means for effecting relative rotation of the valve and the cutters for dressing and truing such valve.

A further object of the present invention is to provide a valve truing device in which certain of the parts are replaceable to adapt the device to operate on valves of various sizes and shapes and having stems of varying diameters.

Other objects and features of the invention reside in the combinations and arrangements of parts and in the details of construction hereinafter more fully described and claimed.

In order that our invention may be more clearly understood, attention is directed to the drawing accompanying and forming a part of this specification, and in which:

Figure 1 is a vertical longitudinal sectional view, partly in elevation, of a valve truing device comprising a preferred embodiment of our invention, with a valve to be trued or refaced operatively mounted therein;

Fig. 2 is a view in end elevation, partly in section, looking from the left in Fig. 1, the valve being omitted; and

Figs. 3 and 4 are enlarged detail views in elevation, partly in section, showing two different forms of the valve engaging pin or stem, carried by the means for adjusting the valve to regulate the cut and for maintaining the valve being trued centered in the device.

Referring to the drawing, the valve truing device illustrated therein comprises a base or frame 1 having vertical brackets or standards 2 and 3 at its ends respectively. The standard 2 is provided at its upper end with a hollow frusto-conical cutter head 4, preferably formed integrally therewith, the inner smaller end of the head facing the standard 3 and having a circular opening 5. The cutting means for the valves to be trued and refaced comprises a plurality of blades or knives 6, which are rigidly secured in suitable guides 6' provided on the inner conical surface of the head 4 as by means of screws 7. There are preferably five of these blades and the same are preferably equi-spaced and arranged at an angle of either 45 degrees or 60 degrees with respect to the axis of the cutter head 4. The blades 6 are positioned and ground very accurately so that corresponding points in the cutting edges thereof will be equi-distant from the axis of the head 4, the blades also being arranged with their cutting edges extending substantially radially with respect to said axis.

An arm 8 is pivotally mounted at 9 at one side of the outer large end of the cutter head and is adapted to extend across said end, as shown, said arm being provided at its free end with a notch 10 adapted to be engaged with the shank of a screw or stud 11 carried by the head 4 at a point diametrically opposite the pivot 9. A rod 12 is threaded through the arm 8 substantially midway between the ends thereof and at such a point that when the arm is positioned as shown, with its notch 10 engaging the stud 11, the axis of the rod will exactly coincide with the axis of the cutter head and also with the axis of the valve chuck or holding means which will presently be described. The rod 12 has a handle

13 at its outer end whereby the rod may be turned to adjust it. The inner end portion of rod 12 is provided with a coaxial cylindrical recess in which a cylindrical pin or 5 stem 14 is mounted. While the stem 14 fits closely in the recess in rod 12 it is free to rotate therein. This stem extends some distance from the rod 12, and its outer end 15 is conical and is adapted to engage and fit 10 the central conical recess usually provided in the heads of poppet valves for internal combustion engines. The inner end of the pin or stem 14 is provided with a spherical recess or ball socket and a ball 16 is rotatably 15 mounted within said recess and protrudes therefrom slightly so as to engage the bottom of the recess in the rod 12, an anti-friction ball thrust bearing thus being provided for the stem or pin. The portion of the stem 20 adjacent the ball 16 is peaned over to retain the ball within its socket.

The standard 3 is provided at its upper end with a journal 17 preferably formed integrally therewith, the axis of this journal and the axis of the cutter head 4 being in exact alignment. A cylindrical shouldered sleeve 18 is slidably and rotatably mounted in the journal 17, the enlarged portion of the sleeve fitting quite closely within the 25 journal, and a helical spring 19 surrounding the reduced portion of the sleeve within the journal, tends to move the sleeve to the left and to maintain the same in a position in which a collar 20 fastened to the sleeve at a 30 point beyond the right-hand end of the journal, is in engagement with the latter. The collar 20 is adjustably secured to the sleeve 18 as by means of a set-screw 21. The sleeve 18 also extends from the journal 17 towards 35 the cutter head 4, and is provided at its left-hand end with an outer flange 22 and with an outwardly flaring conical enlargement 23 of its bore. A radial opening 24 provided in the sleeve 18, is adapted to be engaged 40 by the inner end of a stem 25 slidably mounted in an opening extending radially through the journal 17, said stem having a pin and slot connection 26 with the journal for limiting the movement thereof, and being normally held in its uppermost position out of 45 engagement with the opening 24 by means of a coiled spring 27 which embraces the stem between the head thereof and the journal 17. Disposed and fitting fairly closely 50 within the sleeve 18 is a tubular draw-chuck 28. The draw-chuck 28 is provided at its inner left-hand end with a conical enlargement 29, which conforms to the conical enlargement 23 of the bore of sleeve 18 and is 55 adapted to coat therewith to rigidly secure a valve to be trued in proper position in the device as will presently appear. In order to provide the chuck 28 with resilient jaws, the same is longitudinally kerfed, 60 as indicated at 30. Reference character 31

represents a crank or handle provided with a hub 32 which has a screw-threaded connection with the right-hand end portion of the chuck 28 extending from the sleeve 18. Inserted within the draw-chuck 28 70 from the left-hand end thereof is a removable and interchangeable cylindrical adapter or fill-in chuck 33; the latter being provided with an end flange to limit the distance the same may be pushed into the 75 chuck 28, and being longitudinally kerfed as indicated at 34, to provide resilient jaws. When a valve to be trued is mounted in the device, its stem or shank is received and held in the fill-in chuck 33. The stem of 80 the valve should fit snugly within the adapter chuck 33, and accordingly a number of these chucks having different internal diameters are preferably provided for each truing device to adapt the latter for use with 85 valves having stems of different diameters. It will be apparent that an adapter chuck may be selected which will fit closely the stem of any valve to be dressed, and consequently that the valve may be very accurately centered in the valve holding means comprising the sleeve 18, draw-in chuck 28 and fill-in chuck 33.

Reference character 35 represents an ordinary form of poppet valve such as generally used in internal combustion engines, this valve having the usual cylindrical stem 36. In mounting this valve in our truing device or tool, the arm 8 is thrown back around its pivot 9, and in case the draw-in chuck 28 and adapter chuck 33 have not already been released from their respective frictional locking engagement with the sleeve 18 and chuck 28, this is accomplished by engaging the stem 25 with the opening 24 in sleeve 18 to hold the latter against rotation and then, while holding the stem 25 thus engaged against the action of spring 27, turning the handle 31 in an anti-clockwise direction on the outer threaded end portion of the chuck 28. When the chucks 28 and 33 are thus released their resilient jaws will expand and assume their normal positions. The stem 36 of the valve 35 is then shoved into the cutter head 4 from the outer end thereof, through the opening 5 and into the adapter chuck 33 until the head of the valve is positioned within the cutter head with the face thereof to be dressed and trued in engagement with the blades 6. The arm 8 is then moved back about pivot 9 to its former position with the notch 10 thereof engaging the pin 11, whereupon the rod 12 is turned by its handle 13 until the conical end 15 of the stem or pin 14 carried thereby engages the usual central conical recess in the head of the valve 35. The parts now being in the position shown in Fig. 1, the valve 35 is rigidly secured in its mounting, comprising the 130

sleeve 18, and chucks 28 and 33, this being accomplished by merely turning the handle 31 in a clockwise direction on the outer threaded end portion of the chuck 28 while 5 maintaining the stem 25 in engagement with the opening 24 in sleeve 18 to hold the latter against rotation. On thus turning the handle 31, the hub 32 thereof, because of its threaded connection with the chuck 28, 10 coacts with the adjacent end of sleeve 18 to move said chuck to the right in the sleeve. In such movement of the draw-in chuck 28, the wall of the enlarged conical end portion 23 of the bore of sleeve 18 coacts with the 15 conical enlargement 29 of chuck 28 to contract the resilient jaws of the latter, which in turn contract the resilient jaws of the fill-in chuck 33 into firm gripping engagement with the valve stem 36. The valve 20 will then be rigidly secured in its mounting. But a slight turning of the handle 31 relative to the chuck 28, is necessary either to secure the valve in its mounting or to effect the release of the gripping engagement of 25 the fill-in chuck 33 with the valve stem so as to permit the valve to be removed from the device.

When the valve has been rigidly secured in its mounting, as above described, pressure is removed from the stem 25 and the 30 spring 27 will thereupon act to disengage the stem from the opening 24 in sleeve 18. Turning of the handle 31 will now effect rotation of the valve mounting comprising 35 sleeve 18 and chucks 28 and 33, together with the valve 35 about the axis of journal 17, and such rotation of the valve will, of course, result in the cutting or dressing of the face thereof to be trued by the stationary blades 6. The extent to which the 40 face of the valve is dressed or cut away, as well as the depth of the cut, may be nicely regulated by adjustment of the rod 12, for the further the rod is screwed inwardly through the arm 8 the further the 45 valve will be moved to the right towards the blades 6 in opposition to the action of the spring pressure on the spring-pressed mounting for the valve. In this connection, it will be seen that as the rod 12 is 50 screwed inwardly and the valve forced to the right thereby, the chucks 28 and 33 and sleeve 18 will also be moved to the right in the journal 17, such movement being 55 permitted but opposed by the spring 19. It will also be apparent that the spring will act through the valve mounting to yieldingly but firmly maintain the valve in engagement with the centering pin 14. 60 carried by the rod 12, and that the said pin and the valve mounting will act to maintain the valve accurately centered in the device, that is, in exact axial alignment with the cutter head 4, throughout the dressing and truing operation. The effective

spring-pressure on the valve mounting may be regulated by adjustment of the position of collar 20 on the sleeve 18.

As the valve 35 is rotated, the pin 14 by reason of its engagement with the conical recess in the center of the valve head, will also be rotated in the rod 12. The provision of the pin 14 with the ball-thrust pivot 16, however, reduces the friction between the pin 14 and rod 12 to a minimum. 70 The heads of poppet valves for internal combustion engines are sometimes provided with small central convex projections instead of with central conical recesses, and when such a valve is to be trued, the centering pin 14, shown in Figs. 1 and 3, is replaced by a centering pin 14', such as shown in Fig. 4, having a head 15' provided with a concave recess 15'' formed to take over and snugly fit the central convex projection 80 on the head of the valve.

A feature of our invention which is of considerable importance, resides in the provision of a single member, viz, the handle 31, for effecting rotation of the valve with 90 respect to the cutter head during the truing operation and also for effecting or controlling the securing of the valve firmly in the mounting therefor and the releasing of the valve therefrom.

In order to enable the operator to view the cutting of the valve from above during the truing operation and to properly regulate the same by adjustment of the rod 12, the upper part of the wall of the frusto-conical 100 cutter head 4 is provided with a pair of fairly large openings O extending therethrough.

While we have shown and described the preferred embodiment of our improved valve truing device, it is to be understood 105 that such embodiment is subject to various modifications and changes in the size, shape and arrangement of parts without departing from the spirit of the invention or the scope of the appended claims.

Having now described our invention, what we claim and desire to protect by Letters Patent is as follows:

1. In a device of the class described, a cutter head, means comprising a member adapted to coact with a valve mounted in the device and adjustable to move said valve against the cutting means of said head, and a spring-pressed mounting in which the valve is adapted to be secured and which is 115 adapted to yieldingly hold the valve firmly in engagement with said member, said mounting comprising means adapted to rigidly hold the valve in the mounting.

2. In a device of the class described, a 125 cutter head, means comprising a member adapted to coact with a valve mounted in the device and adjustable to move said valve against the cutting means of said head, and a spring-pressed mounting in which the 130

valve is adapted to be secured and which is adapted to yieldingly hold the valve firmly in engagement with said member, said mounting comprising means adapted to 5 rigidly hold the valve in the mounting, and said cutter head and mounting being relatively rotatable.

3. In a device of the class described, a cutter head, means comprising a member 10 adapted to coact with a valve mounted in the device and adjustable to move said valve against the cutting means of said head, a spring-pressed mounting in which the valve is adapted to be secured and which is adapted 15 to yieldingly hold the valve firmly in engagement with said member, said mounting comprising means adapted to rigidly hold the valve in the mounting, and means adjustable to vary the effective spring-pressure on said mounting.

4. In a device of the class described, a cutter head, spring-pressed means adapted to grip the stem of a puppet valve to be trued and hold the valve in a position with 25 its head in operative relation to the cutting means of said cutter head, and means adapted to coact with the head of such valve and adjustable to force said head towards said cutting means against the action of the 30 spring-pressure acting on said gripping means.

5. In a device of the class described, valve cutting means, a valve mounting, and unitary means for effecting the securing of a 35 valve in said mounting and for effecting relative rotation of said valve mounting and said cutting means.

6. A valve truing device of the class described, comprising a cutter head, a valve 40 mounting comprising means for rigidly holding a valve therein, said cutter head and valve mounting being relatively rotatable, and means for maintaining a valve accurately 45 centered in the device during the truing operation including said mounting and also including a member adjustable to regulate the position of the valve with respect to said head.

7. A valve truing device of the class 50 described, comprising a cutter head, a valve mounting comprising means for rigidly holding a valve therein, said cutter head and valve mounting being relatively rotatable, and means for maintaining a valve accurately 55 centered in the device during the truing operation including said mounting and also including a member adjustable to regulate the position of the valve with respect to said head, said cutter head, valve mounting and member being in axial alignment during 60 said truing operation.

8. In a device of the class described, a cutter head, a rotatable valve mounting comprising means for rigidly holding a valve 65 therein, and means for adjusting a valve

carried by said mounting with respect to said head comprising an adjustable member, a valve engaging member rotatable with respect to said adjustable member, and an anti-friction bearing between said members. 70

9. In a device of the class described, a cutter head, a rotatable valve mounting comprising means for rigidly holding a valve therein, and means for adjusting a valve carried by said mounting with respect to 75 said head comprising an adjustable rod, a member rotatably mounted in said rod and extending therefrom and a ball thrust bearing between said member and said rod.

10. In a device of the class described, a cutter head, a rotatable valve mounting adapted to hold a valve in operative relation to said head, and unitary means for effecting the securing of a valve in said mounting and for rotating the latter. 80

11. In a device of the class described, a cutter head, a rotatable valve mounting adapted to hold a valve in operative relation to said head, and unitary means for effecting the release of a valve from said mounting 90 and for rotating the latter.

12. In a device of the class described, a cutter head, a rotatable valve mounting adapted to hold a valve in operative relation to said head, and unitary means for effecting the securing of a valve in said mounting, 95 for effecting the release of the valve from said mounting, and for rotating the mounting.

13. A valve truing device of the class described, comprising a cutter head, a valve mounting comprising means for rigidly holding a valve therein, and means for maintaining a valve accurately centered in the device during the truing operation including 100 said mounting and also including a member adjustable to regulate the position of the valve with respect to said head, said mounting being spring-pressed to yieldingly hold the valve firmly in engagement with 105 said adjustable member during the truing operation.

14. A valve truing device of the class described, comprising a cutter head, a valve mounting comprising means for rigidly holding a valve therein, and means for maintaining a valve accurately centered in the device during the truing operation including 110 said mounting and also including a member adjustable to regulate the position of the valve with respect to said head, said cutter head, valve mounting and member being in axial alignment during said truing operation, said mounting being spring-pressed to yieldingly hold the valve firmly 115 in engagement with said adjustable member during the truing operation.

15. In a valve truing device of the class described, a cutter head, a valve mounting for holding a valve in operative relation to 120

- 5 said head comprising a rotatable sleeve, valve chuck means carried by said sleeve and movable relatively thereto to secure a valve in the mounting and to release the 30 valve, means for holding said sleeve against rotation, and means adapted upon actuation thereof when said sleeve is held against rotation, to effect such movement of the chuck 35 means relative to the sleeve.
- 10 16. In a valve truing device of the class described, a cutter head, a rotatable valve mounting for holding a valve in operative relation to said head comprising an outer sleeve, valve chuck means mounted in said 40 sleeve and movable axially with respect thereto to secure a valve in the mounting and to release the valve, means for holding the sleeve against rotation, and means adapted when said sleeve is held against rotation 45 to effect such axial movement of the chuck means.
- 15 17. In a valve truing device of the class described, a cutter head, a rotatable valve mounting for holding a valve in operative 50 relation to said head comprising an outer sleeve, valve chuck means mounted in said sleeve and movable axially with respect thereto to secure a valve in the mounting and
- 20
- 25

to release the valve, means for holding the sleeve against rotation, and means adapted 30 when said sleeve is held against rotation to effect such axial movement of the chuck means, said chuck means comprising an outer chuck and an adapted chuck removably and replaceably mounted within said 35 outer chuck.

18. In a valve truing device of the class described, a cutter head, a rotatable valve mounting for holding a valve in operative 40 relation to said head comprising an outer sleeve, valve chuck means mounted in said sleeve and movable axially with respect thereto to secure a valve in the mounting and to release the valve, means for holding the sleeve against rotation, and means adapted 45 when said sleeve is held against rotation to effect such axial movement of the chuck means, said chuck means comprising an outer chuck and an adapter chuck removably and replaceably mounted within said outer 50 chuck, said chucks having resilient jaws.

This specification signed this 10th day of November, 1921.
